UNITED STATES PATENT OFFICE.

DENISON C. PIERCE, OF CHICAGO, ILLINOIS.

DIE FOR THE MANUFACTURE OF CAPS FOR RAILROAD-FROGS.

SPECIFICATION forming part of Letters Patent No. 224,607, dated February 17, 1880.

Application filed July 3, 1879.

To all whom it may concern:

Be it known that I, DENISON C. PIERCE, of Chicago, in the county of Cook and State of Illinois, have invented certain new and useful 5 Improvements in Dies for the Manufacture of Caps for Railroad-Frogs; and I do hereby declare that the following is a full, clear, and exact description of the invention, which will enable others skilled in the art to which it applies to make and use the same, reference being had to the accompanying drawings, and to letters of reference marked thereon, which form a part of this specification.

Figure 1 is a side elevation of my improved 15 dies open, ready for the reception of the frog-plate. Fig. 2 is an end view, showing the cutters for shaping one end of the plate. Fig. 3 is a longitudinal section of the dies with the heated plate inserted and the operation of 20 pressing commenced on the point of the cap. Fig. 4 is an end view, showing the cutters for shaping the opposite end of the cap-plate from that shaped by the cutters shown in Fig. 2. Fig. 5 is a longitudinal vertical section of the 25 dies closed completely on the frog-plate, but with the punches held back out of contact with the plate. Fig. 6 is a transverse vertical section on line xx of Fig. 5, showing the punch-plate closed upon the upper die and the 30 punches driven through the frog-plate. Fig. 7 is a top view of the completed cap-plate.

The same letter indicates the same part in all the figures where it occurs.

The object of my invention is to press the 35 steel caps of railroad-frogs in one or more pieces by hydraulic or other power, thereby reducing the cost of manufacture. By this process frog-plates may be made from plate-steel, in place of casting from crucible, Bessemer, or other ductile steels, or making them by the process of forging.

The nature of the invention consists in subjecting a plate of steel heated to the proper temperature to the action of a single pair or 45 series of male and female dies of peculiar construction, and operated by hydraulic or other adequate power, whereby the steel plate is caused to assume the desired form. The plate may be pressed complete by one pair or set of 50 dies, or two or more sets may be used. In the latter case one set of dies may be used to form

the point, a second set to finish the point and form the sides, and a third to punch the holes. The power to operate the dies may be applied on one or both sides and in either direction, 55 as may be preferred. I have essayed with success the use of a press whose upper platen is fixed and the lower one movable.

In the drawings I have illustrated a set of compound dies, in which the heated plate is 60 successively subjected to the action of properly-configurated surfaces for forming the point and for fashioning the sides of the cap, and to punches for making the holes by means of which it is to be fixed in position. 65

The male die M is formed in two parts—a movable section, B, which forms the point of the cap, and the main body, which presses up the rest of the plate. The section B rests in a recess upon two eccentric rollers, ee, provided 70 with cranks pivoted to a bar and operated by the lever L, by means of which this section of the die may be raised or lowered, as desired.

Above the male die M is located the female die F, the under side of which has a configuration corresponding conversely to that of the die M and to the form of the finished plate. It is provided with three eccentric rollers, eee, like those supporting section B, having cranks C, pivoted to bar D, which is pivoted to lever 80 E, so that that lever can operate the eccentrics and raise and hold up the plate A or allow it to descend, as required.

To plate A are attached a number of punches, p, which pass down through die F, and when 85 the plate A is in contact with the upper surface of that die enter, by their points, holes provided to receive them in die M. (See Figs. 1 and 6.)

$a a$ $b b$ and $c c$ $d d$ mark the cutting edges at the 90 ends of the dies for shaping the ends of the frog-plate, giving it the projections $f f$ and $g g$, as shown in Fig. 7. $h h$ indicate the holes by means of which and suitable spikes or bolts the finished cap is fixed in position.

The operation of making the frog-plate is as follows: The dies F M are attached to the bed-plate and platen of a hydraulic or other suitable press having the necessary power. Either the upper or lower platen, or both, may be 100 movable, as preferred. The dies are separated, as shown in Fig. 1, for the introduction of the

heated steel plate P, the movable section B of the male die M being raised to its highest level by the eccentrics e, so that that portion of the die shall be first brought into operation upon the plate to form the point G. The plate A is also raised to its greatest height, in order to withdraw the punches p within the die F, by means of lever E or other mechanical means and the eccentrics operated by it. The force 5 of the press is now applied, and the point G having been formed between section B and die F, section B is allowed gradually to retire into its recess in die M while the main body of that die is co-operating with die F in forming the remainder of the frog-plate. When the dies 10 are brought completely home the plate D is allowed to descend, the support of eccentrics e being withdrawn from under it by means of lever E, when the power of the press drives the punches p through the frog-plate P, forming 15 the holes h for the attachment of the plate in position.

The plate may be withdrawn for reheating during the process, if found desirable.

25 Having fully described my invention, what I claim, and desire to secure by Letters Patent, is—

1. The combination of the male die M, pro-

vided with the movable section B, and mechanism for raising and lowering the same, with 30 the female die F, for the purpose of forming the point of the frog plate by the first operation of the dies, as specified.

2. The combination, with the female die F', of the main body of the male die, having the 35 movable section B, provided with eccentric rollers e, and mechanism for operating them to raise and lower the section B, all as and for the purpose specified.

3. The combination, with the female die F, 40 of the plate A, provided with the punches p, eccentrics e, cranks C, rod D, and lever E, all constructed and operating substantially as and for the purpose described.

4. Jointly with the dies constructed as de- 45 scribed, the cutters a a b and c c d, arranged and operating in the manner and for the purpose specified.

In testimony that I claim the foregoing as my own invention I affix hereto my signature 50 in presence of two witnesses.

DENISON C. PIERCE.
